UNITED STATES PATENT OFFICE.

SIDNEY GEORGE BROWN, OF NORTH ACTON, LONDON, ENGLAND.

DEVICE FOR TRANSMITTING OR REPRODUCING SOUND.

Application filed February 4, 1925, Serial No. 6,870, and in Great Britain May 27, 1924.

This invention relates in general to devices for transmitting or reproducing sound and more particularly to devices such as microphones, telephone receivers and gramophones.

In devices of the kind referred to above the vibrating element is usually in the form of a disc-like diaphragm stretched over a member and clamped to this member around its outer edge by suitable means, the vibrations being imparted to the centre of such diaphragm.

A certain amount of distortion of the vibrations occurs in a diaphragm of this kind owing to its having a very marked natural period of vibration and consequently the sounds produced by such a diaphragm are more or less distorted. Again, the amplitude of the vibrations of such a diaphragm is affected by the clamping around its edge.

One object is to overcome these disadvantages and the invention consists in the novel features hereinafter described and more particularly pointed out in the claims.

Referring now to the accompanying drawings which illustrate by way of example an embodiment of the invention:

Figure 1 shows the top half of the vibrating element in section;

Figure 2 shows the bottom half of the vibrating element in section;

Figure 3 shows the vibrating element in section;

Figure 4 shows the vibrating element applied to a loud-speaker;

Figure 5 shows the vibrating element applied to an ordinary ear telephone.

Figure 6 shows a modification of the vibrating element, and

Figure 7 shows a magnetic element attached to the modified form.

In carrying the invention into effect according to one form as illustrated in Figures 1 to 3, the vibrating element comprises a thin sheet metal envelope forming what I prefer to call a double or capsule diaphragm, the two opposing faces, *a*, *b*, of which are separated by an air space, *c*. Each face of my capsule diaphragm is preferably formed from a metal disc so as to have a flat annular portion, *d*, and a conical portion, *e*, forming a depression therein, each face being a surface of revolution.

The face, *a*, Figure 1, which will be hereinafter called the outer face, has the apex

of the cone removed and around the hole made thereby is formed in the interior of the cone by spinning or other means a flange, *f*, projecting upwards toward the flat annular portion, *d*, in a direction parallel to the axis of said cone. The outer periphery of the flat annular portion is provided with a flange, *g*, parallel to the flange in the interior of the cone but pointing in the opposite direction, i. e. downwards.

The other face, *b*, Figure 2, hereinafter referred to as the inner face of my capsule diaphragm, is similar to the outer face, *a*, except that the flange, *h*, at the periphery of the flat portion, *d*, projects in the opposite direction. The two faces are placed together with the apices of the cones on the same side and united by the flanges, *g* and *h*, which separate the two faces and form an air space between them. The top of the cone is spun over so as to form a small flat circular part, *j*, parallel to the flat portion, *d*. The flat or annular portion, *d*, of the two faces have grooves, *k*, spun therein to increase flexibility. These may be omitted if desired.

The two faces being similar, the air space, *c*, between them is uniform in thickness and this thickness can be made of any desired value according to the distance separating the two faces. The capsule diaphragm is preferably enclosed in or substantially surrounded by a casing when in use.

In applying the capsule diaphragm to a loud-speaker as illustrated in Figure 4, the flat part, *j*, at the conical end of the inner face, *b*, is attached to a reed, *l*, or other member by a screw or other means, the reed, *l*, being given sinusoidal vibrations electromagnetically in the usual manner within the body or casing of the loud-speaker.

The base plate, *m*, to which the sound directing means or horn of the loud-speaker is attached is provided with an inwardly projecting portion, *n*, which has an aperture, *o*, of such a size that the flange, *f*, in the outer face, *a*, of the capsule diaphragm fits tightly therein. The sides of the extension, *n*, are made conical so as to fit accurately to the portion, *e*, of the outer face, *a*, of the capsule diaphragm and thus support the whole of the flange, *f*. The capsule diaphragm is thus substantially surrounded by the body or casing of the loud-speaker. Any suitable means may be employed to rigidly secure this flange to the

horn base and means other than the above-mentioned flange may be employed for securing the capsule diaphragm rigidly in the desired position.

5 Figure 5 shows the capsule diaphragm attached to an ordinary ear-piece telephone. The interior of the flange, *f*, and part of the outer face, *a*, are attached to a collar, *u*, while the exterior of the flange, *f*, is attached to a supporting member, *v*, which in turn is positioned by a cylindrical member, *w*, mounted upon the body, *x*, of the telephone. The sound directing means or ear-piece, *y*, is screwed on to the body, *x*, and 10 presses the member, *v*, tightly against the cylindrical member *w*, thus forming a casting enclosing the capsule diaphragm. The faces, *a* and *b*, are united by the flanges, *g* and *h*, and the face, *b*, is attached to the 15 reed *l*, by suitable means such as a screw.

This method of attaching the capsule diaphragm may also be applied to loud-speakers.

According to a modification as illustrated 20 in Figure 6, the two faces of the capsule diaphragm are formed of two flat discs, *p*, *q*, joined together at their peripheries by a flange, *r*. The outer disc, *p*, is provided with an aperture having a flange, *s*, surrounding it. This flange, *s*, is attached to the usual ear-piece (not shown) by expanding or other suitable means. The face, *q*, may be of magnetic material and situated directly over the magnets of the telephone, 25 or it may be made of metal or other material and attached directly to a reed as shown in Figure 4 or a suitable magnetic member, *t*, may be attached to *q* as shown in Figure 7 which will be attracted by the 30 telephone magnets.

The capsule diaphragm being rigidly held only at the centre of the outer face is therefore free to vibrate as a whole except at this point.

45 My capsule diaphragm is preferably made of thin sheet aluminium spun to the desired shape, although any other suitable metal may be employed, the two faces being spun separately and then united together by spinning, welding, soldering or any other suitable means. If desired, the capsule diaphragm can be formed by stamping, pressing or other suitable means, in one or more pieces, and need not be made of metal but 50 of any other suitable material.

The surfaces of my capsule diaphragm may be flat, curved or any other desired shape and the two faces may be dissimilar so that the thickness of the air space can be varied at different points and the shape need not be circular but may be oval, square, 55 polygonal or other suitable shape.

The inner face of my capsule diaphragm may be formed of a magnetic material or 60 may have a magnetic portion attached there-

to, and may be situated above the electro-magnets to which the electrical impulses are supplied to cause the vibrations.

It will be seen from the description given above that the capsule diaphragm is rigidly supported only around the centre of one face and that both faces are free to vibrate in a bellows-like manner, there being no restriction whatever at the outside edges. Such a diaphragm has no marked period of natural vibration and consequently it responds accurately to any vibration which may be impressed thereon with the result that the sound vibrations emitted by such a diaphragm are substantially free from any distortion.

My capsule diaphragm as described above may be applied to any device in which a vibrating element is employed.

Having now described my invention, what I claim as new and desire to secure by Letters Patent is:—

1. A device for transmitting or reproducing sound comprising in combination a bellows-like sound capsule formed of two diaphragms joined together at their peripheries and spaced apart, one of said diaphragms being apertured to emit sound; means for supporting one of said diaphragms in the region of its centre; a reed attached to the other of said diaphragms in the region of its centre and on the side of the said diaphragm remote from said first-mentioned diaphragm and means for vibrating said reed.

2. A device for transmitting or reproducing sound comprising in combination a bellows-like sound capsule formed of two diaphragms joined together at their peripheries and spaced apart, one of said diaphragms having an open sound-emitting hole at the centre thereof; a support for said diaphragms; means for rigidly securing said holed diaphragm to said support in the region of said hole; a reed attached to other of said diaphragms; means for vibrating said reed; and a surrounding casing positioning said diaphragm support.

3. A device for transmitting or reproducing sound comprising in combination a bellows-like sound capsule formed of two diaphragms joined together at their peripheries and spaced apart, one of said diaphragms having an open sound-emitting hole at the centre thereof; means for supporting said diaphragm in the region of said hole; a reed attached to the other of said diaphragms and disposed on the side thereof remote from said first-mentioned diaphragm and means for vibrating said reed.

4. In a device for transmitting or reproducing sound, the combination comprising a vibrating element composed of two opposed diaphragms connected together at their peripheries to form an enclosed space, each dia-

phragm having a conical portion and a flat annular portion, a casing substantially surrounding said element, means for rigidly attaching the conical portion of one of said diaphragms to said casing, and means for imparting vibrations to the other of said diaphragms, as set forth.

5. In a device for transmitting or reproducing sound, the combination comprising a 10 vibrating element having two similar diaphragms opposed to one another, means for connecting said diaphragms together at their peripheries to form an enclosed space of uniform thickness, means for directly causing one of said diaphragms to vibrate, a sound 15 directing member, and means for rigidly connecting the centre of said other diaphragm to said sound directing member, as set forth.

6. In a device for transmitting or reproducing sound, the combination comprising a 20 vibrating element composed of two opposed diaphragms connected together at their peripheries to form a bellows-like sound capsule, each diaphragm having a conical portion and a flat annular portion, one of said diaphragms being apertured to emit sound, a casing substantially surrounding said element, means for rigidly attaching the conical portion of one of said diaphragms to said 25 casing a reed attached to the conical portion of the other of said diaphragms and means for imparting vibrations to said reed, as set forth.

In testimony whereof I have signed my 30 35 name to this specification.

SIDNEY GEORGE BROWN.
